UNITED STATES PATENT OFFICE.

BENJAMIN FRANKLIN ROGERS, OF BUFFALO, NEW YORK.

SECTIONAL FURNACE FOR HOT-WATER HEATING.

No. 839,647.

Specification of Letters Patent.

Patented Dec. 25, 1906.

Application filed November 7, 1905. Serial No. 286,310.

To all whom it may concern:

Be it known that I, BENJAMIN FRANKLIN ROGERS, a citizen of the United States, residing at Buffalo, in the county of Erie and State of New York, have invented a new and useful Sectional Furnace for Hot-Water Heating, of which the following is a specification.

This invention relates to boilers, and while particularly intended for that type employed 10 in hot-water heating systems it is capable of advantageous use in other analogous relations.

One of the principal objects is to provide a structure having a comparatively great heating-surface and wherein a portion of said surface is embedded directly in the hottest part 15 of the fire, said structure, moreover, being exceedingly economical in the amount of fuel necessary to operate it.

Another and important object is to provide a novel boiler wherein the furnace is divided into a plurality of compartments in either or both of which fire may be maintained in order to conveniently vary the heating 25 capacity of the boiler.

A still further object is to provide a novel system of flues through which the products of combustion pass before escaping, said flue system being intimately associated with the 30 water to be heated, and thereby insuring the absorption of practically the entire heat from the products of combustion.

The preferred embodiment of the invention is illustrated in the accompanying drawings, wherein—

Figure 1 is a perspective view of one type of the boiler with the front section removed. Fig. 2 is a view in elevation of the rear section of the boiler. Fig. 3 is a view in rear 35 elevation of the front section of the boiler. Fig. 4 is a vertical sectional view through the complete boiler. Fig. 5 is a horizontal sectional view substantially on the line 5-5 of Fig. 4. Fig. 6 is a detail horizontal sectional view, on an enlarged scale, through a portion 45 of the partition formed by the water-legs.

Similar reference-numerals designate corresponding parts in all the figures of the drawings.

In the embodiment illustrated the furnace 50 is made up of a front section 7, a rear section 8, and a plurality of intermediate sections 9, any number of which may be employed as desired. These various sections are supported on a suitable base 10, having a grate 11 extending from end to end thereof, which

grate may be of any desired construction. The various sections each consist of a water-containing top 12 and depending water-containing side wall elements 13, the latter 60 of which are outwardly bulged, as shown. The lower ends of the side wall elements extend downwardly to the grate and rest upon the base 10, as shown, said lower ends of each section being independent. Each section is 65 furthermore provided with an intermediate depending water-containing leg 14, which depends toward the grate and in the present embodiment terminates short of the same, though the length of this water-leg may be 70 varied considerably without departing from the spirit of the invention. Furthermore, while a central leg is shown in the present embodiment it will be evident that each boiler-section may be provided with a number 75 of said legs.

It will be observed that the opposite side faces of the boiler-sections are flat, so that they will abut closely together, and consequently when together the side wall elements 80 13 form opposite continuous-water-containing side walls, while the intermediate legs being also abutted constitute a continuous intermediate water-containing partition. The various sections are held together by tie-bolts 15 passing through integral sleeves 16, that bridge the different sections, said tie-bolts thus rigidly maintaining the parts in assembled relation. Water communication is established through the different side-wall 90 elements through push-nipples 16, located in aligned openings 17, formed in the lower ends of the side-wall elements, the lower ends of the legs being also in communication through push-nipples 18, disposed in openings formed in the adjacent sides of said legs and clearly shown in Fig. 4 of the drawings. The tops of the boiler-sections are also in communication through similar push-nipples 95 19. It will thus be apparent that water 100 can circulate freely through the entire boiler. One or more outlet-nipples, as 20, are preferably formed in the top of the boiler, and nipples 21, formed in the sides of said boiler, constitute means for connecting the return-pipes 105 thereto.

By the arrangement above disclosed it will be seen that the interior of the boiler is divided by the water-legs into separate combustion-compartments, and these compartments have separate communication with a smoke-outlet 22. This communication is 110

afforded through indirect flues formed in the tops 12 of the sections. In the present embodiment the intermediate sections are provided in their tops with outer and inner flue elements 23 and 24, that are completely surrounded by water and when the boiler-sections are secured together form spaced sets of outer and inner flues, as will be evident by reference to Fig. 5. The front section 7 is provided with a pair of comparatively large flue elements 25, which communicate with both flue elements of each set of the adjacent sections. Consequently the inner and outer flues 23 and 24 are in communication at the front end of the boiler. The rear section 8 is provided with a pair of uptakes 26, that constitute the means of communication between the different combustion-compartments and the outer flues 23. This will be evident by reference to Fig. 5. Said rear section 8, furthermore, has a pair of inner flue elements 27, that align with the inner flue elements 24 of the intermediate sections and constitute the means of communication between the same and the smoke-outlet 22. By this arrangement it will be seen that each combustion-compartment has its independent and indirect flue connection with the smoke-outlet and that these flue connections, as well as the combustion-compartments, are water-enclosed. It will of course be understood that suitable doors are provided for the different flues, combustion-compartments, and ash-pit. In operation if a fire is built in both the combustion-compartments the depending water-legs or intermediate partition will be embedded therein, and consequently in the hottest part of the fire. Moreover, the products of combustion are required to traverse the comparatively long indirect flues, so that the heat is almost completely absorbed by the surrounding water, and actual experience has demonstrated that the smoke-pipe will be cold. Moreover, with this structure no great draft is necessary, and instead of actual flame in order to heat the water it is sufficient to have the coal merely glowing, as the water-leg is depending directly within the same. The result is an exceedingly-economical and highly-effective furnace. Another advantage secured by the depending intermediate partition resides in the fact that in comparatively warm weather, but when heat is necessary and the full capacity of the furnace is not required, fire may be maintained in one combustion-compartment only, and as this compartment has its own flue connection with the smoke-outlet the fire may be properly maintained therein. Furthermore, heating devices of different characters—as, for instance, gas or oil burners—may be employed in the different compartments, if desired. In addition to the above advantages it will be evident that the boiler is very

simple in construction and that the size of the same may be varied by merely introducing intermediate boiler-sections and employing different lengths of bases and grates. Furthermore, the different sections may be readily removed and replaced, so that in case an accident should occur to any section the same may be supplanted with a new one without the cost of an entirely new boiler.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. A boiler of the character described, comprising a grate, a plurality of hollow sections, each having top and side-wall elements, and an intermediate water-containing leg depending from the top element between the side-wall elements, the side-wall elements of the different sections being located together, forming furnace side walls, and the legs being located against each other, forming a continuous intermediate furnace-partition between the side walls and located over an intermediate portion of the grate, tie devices and water-conducting means connecting the side-wall elements, and tie devices and water-conducting means connecting the lower portions of the abutted legs.

2. A boiler of the character described, comprising a plurality of hollow sections, each having top and side-wall elements, and an intermediate water-containing leg depending from the top element between the side-wall elements, the side-wall elements of the different sections being located together, forming furnace side walls, and the legs having opposite flat sides abutted against each other, forming a continuous intermediate furnace-partition between the side-walls, tie-bolts passing through the side-wall elements, nipples connecting the adjacent side-wall elements, a tie-bolt passing through the legs, and nipples connecting the adjacent legs.

3. In a boiler of the character described, the combination with a grate, of a boiler-body comprising abutted sections, said sections, each consisting of a top, independent water-containing side-wall elements depending from the top to the sides of the grate, and intermediate water-containing legs depending from the top toward an intermediate portion of the grate, said side-wall elements being abutted, and said intermediate legs being abutted, forming separate combustion-compartments over the grate, tie-rods passing

through the side walls and through the intermediate legs, and water-conducting means connecting the abutted side-wall elements and the abutted legs to permit the circulation of water through the side walls and through the intermediate partition formed by the depending legs.

4. A boiler of the character described, comprising sections, each section including top and depending side-wall elements having water-chambers therein, and flue-openings formed through the water-chambers of the tops of the various sections, said boiler-sections being abutted with the flue elements in alinement, and the flues formed thereby extending longitudinally through the boiler.

5. A boiler of the character described, having top, side walls, and an intermediate water-leg partition depending from the top and forming separate combustion-compartments, said top having a water-chamber therein and separate flues extending longitudinally through the water-chamber of the top, and communicating respectively with the different combustion-compartments.

6. In a boiler of the character described, the combination with a water-containing top, water-containing side walls, and an intermediate water-containing partition forming separate combustion-chambers within the boiler, of a smoke-outlet, and separate indirect flues extending longitudinally through

the water-containing top and surrounded by the water in said top, said flues independently connecting the different compartments to the smoke-outlet.

7. In a boiler of the character described, the combination with a base, of a furnace-grate located thereon and extending from end to end thereof, and a boiler-body mounted on the base and comprising end and intermediate sections, said sections each comprising a water-containing top, independent outwardly-bulged side-wall elements extending to the opposite sides of the base, intermediate depending water-containing legs, the side-wall elements and intermediate legs of the different sections being abutted, forming outer side walls, and an intermediate partition dividing the space within the body into separate combustion-compartments over the grate, a smoke-outlet at one end of the boiler, and independent indirect flues extending longitudinally through the water-containing top of the furnace and separately connecting the different combustion-compartments with the smoke-outlet.

Signed at Buffalo, in the county of Erie and State of New York, this 31st day of October, 1905.

BENJ. FRANKLIN ROGERS.
